Honorable Miller

Attorney.

UNITED STATES PATENT OFFICE

JESSE D. LANGDON, OF LOS ANGELES, CALIFORNIA, ASSIGNOR TO LANGDON ENGINEERING CORPORATION, OF LOS ANGELES, CALIFORNIA

INDICATOR

Application filed December 15, 1927. Serial No. 240,299.

The present invention relates to indicators and registers, and aims to provide a novel and improved device for indicating the quantity of material delivered or other operations, and although the device is intended especially for use with a dispensing pump for indicating the quantity of grease, oil or other material dispensed, the device is useful for other purposes also to indicate quantity, operations, or the like.

Another object is the provision of novel means for operating an indicating member by the reverse motions of the pump or other machine with which the device is used.

15 A further object is the provision of an indicating device which may be conveniently assembled with a dispensing pump.

Still another object is the provision of an indicator of the kind mentioned comprising 20 a novel assembly of the component elements.

With the foregoing and other objects in view, which will be apparent as the description proceeds, the invention resides in the construction and arrangement of parts, as 25 hereinafter described and claimed, it being understood that changes can be made within the scope of what is claimed, without departing from the spirit of the invention.

The invention is illustrated in the accompanying drawings, wherein—

Figure 1 is a front view of the indicator as applied to a dispensing pump, portions being shown in section.

Fig. 2 is a section on the line 2—2 of Fig. 1. 35 Fig. 3 is a cross section on the line 3—3 of Fig. 2.

The indicator comprises an elongated shell or case having the back 7, sides 8 integral with the back, and a removable front or face plate 9 provided with bent back edges 10 to engage slidably behind the outturned flanges 11 at the forward edges of the sides 8. The front plate 9 may be slid longitudinally into and out of engagement with the sides 8 when 40 assembling and separating the parts. A guide 12 of U-shaped cross-section is fitted and secured within the case between the sides 8, with its edges extending rearwardly, as seen in Fig. 3. The guide is spaced from the front plate 9 to provide a slideway for

the indicating member or slide 13. Said member 13 bears frictionally against the rear surface of the front plate 9, and said front plate has an opening 14 to expose the numerals or other indicia printed, stamped or otherwise provided on the slide 13. The ends 15 of the slide are bent rearwardly to bear frictionally against the guide 12, in order that the slide 13 will remain in any position to which it is moved, said slide being disposed tightly between the front plate 9 and guide 12 but being free to be forcibly moved. The slide 13 has ratchet teeth 16 on the rear surface thereof.

As shown, the device is used in a vertical or upright position, and a restoring plunger 17 is slidable through the top or upper end 18 of the case, and has a fingerpiece 19 for conveniently pushing the plunger 17 downwardly. Said plunger moves between the front plate 9 and guide 12 and is adapted to contact with the upper end of the slide 13, for pushing said slide downwardly to initial or starting position. The top or end 18 of the case is integral with the upper end of the front plate 9, and has an upstanding flange 20 to overlap the upper end of the back 7, said flange 20 and back being provided with apertures 21' adapted to register in order to receive a seal or lock to prevent the front plate 9 being moved open without breaking the seal or opening the lock.

A slide 21 is movable longitudinally in the guide 12, and is reciprocated for advancing the indicating slide 13 step by step. The slide 21 comprises a strip of sheet metal, and has a spring pawl or dog 21a struck therefrom to spring forwardly and engage the ratchet teeth 16, thus providing a ratchet connection between the slides 13 and 21. The guide 12 has an opening 12a through which the pawl 21a is projectible when the slide 21 is moved upwardly, and when said slide moves downwardly the pawl 21a is retracted, as seen in Fig. 2. Thus, the upward movement of the slide 21 permits the pawl 21a to spring forwardly through the opening 12a and to engage the corresponding tooth 16, as seen in dotted lines in Fig. 2, thereby moving the slide 13 upwardly one step with the slide 95 100

21. The return or downward movement of the slide 21 will retract the pawl 21a, and the slide 13 remains in its advanced position due to the frictional engagement of the slide 13 in its slideway.

5 The slide 21 has its lower terminal portion 22 bent rearwardly, and said slide has an upper rearwardly bent portion 23 with an upwardly extending stop 24 bearing against the back 7 of the case and adapted to contact with the top 18 for limiting the upward movement of the slide 21. A screw 25 is screw-threaded through the portion 23 and its adjustment is maintained by means of one or more lock nuts 26.

10 15 The means for imparting reciprocatory motion to the slide 21 from the dispensing pump or other machine with which the indicator is used, comprises a reciprocatory bar 27 slidable in the guide 12 behind the slide 21. The bar 27 slides through a bifurcation in the portion 22 of the slide 21 and also slides in the guide 29 of the case which extends below the front plate 9. The bar 27 has a head or portion 28 between the portion 22 and screw 25 of the slide 21, whereby at the limits of movement of the bar 27, the slide 21 is moved with said bar, the movement of the slide 21 being relatively short while the movement of the bar 27 is considerably longer. Thus, the bar 27 may have a long stroke while the slides 13 and 21 of the indicator may have short movements, and the full movement of the bar 27 is necessary to advance the indicating slide 13.

20 25 30 35 40 45 50 The bar 27 must move to its upper limit in order that the head 28 will contact with the screw 25 and raise the slide 21, so as to lift the slide 13 one step. The bar 27 must then move to its lower limit in order that the head 28 will seat on the portion 22 and move the slide 21 downwardly, said slide 21 being held frictionally between the guide 12 and back 7 of the case. Consequently, the relatively long reciprocatory movement of the bar 27 is converted into a relatively short reciprocatory movement of the ratchet slide 21, which advances the indicating slide 13 one step for each reciprocation, and the full movement of the bar 27 is necessary to actuate the slides 21 and 13, thereby preventing false indications and assuring of correct registration of the material delivered or full operations performed.

55 As shown, the bar 27 is operably connected with a dispensing pump, and for this purpose said bar has teeth 30, and constitutes a rack bar meshing with a pinion 31 housed within a pocket 32 of the guide 29. The rotation of the pinion 31 in reverse directions will reciprocate the rack bar 27, thereby affording convenient connection of the device with a dispensing pump.

60 65 The dispensing pump 33 is of any conventional type, and has a guide 34 in which the rack 35 of a piston or plunger is movable,

being limited in its movement by an adjusting screw or stop 36. Said rack or plunger is reciprocated by means of a pinion 37 secured on a shaft 38 rotatable in a bearing 39. The shaft 38 has a square or non-circular terminal 40 on which a crank 41 is secured by means of a nut 42 or otherwise, whereby the crank may be rotated in opposite directions for ejecting or dispensing the grease, oil, or other substance, as well known.

70 75 80 85 90 95 100 105 In attaching the present indicator to the dispensing pump, the pinion 31 slips over the terminal 40 of the shaft 38, being provided with a square or noncircular hole for that purpose, whereby the rack bar 27 is reciprocated with the rack or plunger 35 of the pump. One side of the pocket 32 has an opening 43 to receive the hub or boss of the pinion 31, to hold said pinion in proper position and journal it for rotation in the pocket 32. The opposite side of the pocket has a larger opening 44 through which the pinion may be moved, in assembling the parts, and a washer or cover plate 45 is disposed across the opening 44 between the crank 41 and pocket 32, to close said opening and conceal the pinion. When the nut 42 and crank 41 are removed, the indicator may be readily placed on or removed from the shaft 38, and the plate 45 may be removed, thereby giving access to the pinion 31 so that it may be removed from the rack bar 27 and the pinion turned to another position when it is desired to adjust the relative positions of the rack bar 27 and rack or plunger 35.

110 115 120 125 A bendable flange or plate 46 is secured to the guide 29 and pocket 32 and is adapted to be bent against the body of the pump 33 or other suitable part in order to prevent the indicator from rotating with the shaft 38 or around the axis of said shaft.

With the device assembled with the pump, as shown and described, whenever the plunger 35 is given one complete reciprocation, the indicating slide or member 13 is advanced one step, so that the slide 13 will indicate, through the opening 14, the quantity of material delivered. If the plunger 15 is not moved the full amount, then the slide 13 will not be advanced, thereby preventing cheating. When the desired quantity of material has been dispensed and the plunger 35 and rack bar 27 are moved downwardly, the indicating slide 13 may be restored to initial position by pushing the plunger 17 downwardly. This resets the indicator.

Having thus described the invention, what is claimed as new is:—

1. An indicator comprising an elongated case, an indicating slide slidably longitudinally therein, a second slide also slidably longitudinally in the case, said slides having cooperable ratchet means for advancing the

- indicating slide step by step by the reciprocation of the second slide, and an actuating member entering the case and slidable longitudinally therein, the actuating member and second slide having cooperable portions adapted to contact at the limits of movement of the actuating member to reciprocate the second slide, the second slide having a short and the actuating member having a long reciprocatory movement.
2. An indicator comprising an elongated case having a removable face plate, an indicator slide slidable longitudinally in said case behind said plate, said plate having an opening through which said slide is visible, a second slide also slidable longitudinally in the case, said slides having cooperable ratchet means for advancing the indicating slide step by step by the reciprocation of the second slide, and an actuating member entering the case and slidable longitudinally therein, the actuating member and second slide having cooperable portions adapted to contact at the limits of movement of the actuating member to reciprocate the second slide, the second slide having a short and the actuating member having a long reciprocatory movement.
3. An indicator comprising an elongated case, an indicating slide slidable longitudinally therein and having ratchet teeth, a second slide also slidable longitudinally in the case and having a pawl to engage said teeth for advancing the indicating slide step by step by the reciprocation of the second slide, an actuating member entering the case and slidable longitudinally therein, the actuating member and second slide having cooperable portions adapted to contact at the limits of movement of the actuating member to reciprocate the second slide, and means for disengaging said pawl from said ratchet teeth when the second slide is moved in a direction opposite to the advance movement of the indicating slide.
4. An indicator comprising an elongated case having a removable face plate, a removable longitudinal guide member in said case behind the face plate, an indicating slide slidable longitudinally in the case and guided by said member, a second slide slidable longitudinally in the case and guided by said member, said slides having cooperable ratchet means for advancing the indicating slide step by step by the reciprocation of the second slide, and an actuating member entering the case and slidable longitudinally therein, the actuating member and second slide having cooperable portions adapted to contact at the limits of movement of the actuating member to reciprocate the second slide, the second slide having a short and the actuating member having a long reciprocatory movement.
5. An indicator comprising an elongated case and guided by said member, a second slide slidable longitudinally in the case and guided by said member, the indicating slide having ratchet teeth, and the second slide having a spring pawl to engage said teeth for advancing the indicating slide step by step by the reciprocation of the second slide, said member having a portion for the contact of said pawl when the second slide is moved in a direction opposite to the advance movement of the indicating slide for disengaging said pawl from said teeth, and an actuating member entering the case and slidable longitudinally therein, the actuating member and second slide having cooperable portions adapted to contact at the limits of movement of the actuating member to reciprocate the second slide.
6. In a meter for liquid dispensing apparatus having a piston for causing the discharge of a predetermined amount of liquid at each full stroke thereof, a sliding scale plate, a casing in which said scale is slidable, a vertical partition plate in said casing having a limited opening therein, a scale actuating plate slidable beside and parallel with said scale plate and adapted to be actuated only at the end of each full dispensing stroke of the piston, and a flexible tongue connected with said scale actuating plate and projecting through the opening in said partition plate in position to actuate said scale and be released from the scale by said partition plate at the end of the return movement of the scale actuating plate.
7. In a meter for liquid dispensing apparatus having a piston for causing the discharge of a predetermined amount of liquid at each full stroke thereof, a sliding scale plate, a casing in which said scale is slidable, a vertical partition plate in said casing having a limited opening therein, a scale actuating plate slidable beside and parallel with said scale plate and adapted to be actuated only at the end of each full dispensing stroke of the piston, a flexible tongue connected with said scale actuating plate and projecting through the opening in said partition plate in position to actuate said scale and be released from the scale by said partition plate at the end of the return movement of the scale actuating plate, and means in said casing for frictionally engaging said scale to resist return movement after any operation thereof.
- In testimony whereof I hereunto affix my signature.
- JESSE D. LANGDON.
